No. 700,711.

Patented May 20, 1902.

F. R. WATERS.

ORE SEPARATOR.

(Application filed May 8, 1901.)

(No Model.)

UNITED STATES PATENT OFFICE.

FREDERICK R. WATERS, OF SALIDA, COLORADO, ASSIGNOR, BY MESNE
ASSIGNMENTS, OF ONE-HALF TO S. O. MALIN AND ROBERT J. POWELL,
OF BALTIMORE, MARYLAND.

ORE-SEPARATOR.

SPECIFICATION forming part of Letters Patent No. 700,711, dated May 20, 1902.
Application filed May 8, 1901. Serial No. 59,267. (No model.)

To all whom it may concern:

Be it known that I, FREDERICK R. WATERS, a citizen of the United States, residing at Salida, in the county of Chaffee and State of Colorado, have invented a new and useful Ore-Separator, of which the following is a specification.

The present invention relates to separators, and is particularly intended for the extraction of gold from auriferous sand, earth, or disseminated rock.

As is well known to those skilled in this art, a large per cent. of gold is in such minute particles or atoms that it passes entirely through an ordinary washer with the worthless portion and is lost. It is furthermore a well-known fact that many localities are rich in this class of gold, but either because of the inability of the machines and methods heretofore employed or the incident expense to recover it these localities have never been worked.

The prime object of this invention, therefore, is to provide a machine of simple construction that will thoroughly separate this class known as "float" or "flour" gold from the material which contains it; and to this end the construction described in the following specification and shown in the accompanying drawings is preferred, although it will be readily understood that changes may be made therefrom as fall within the scope of the claims hereto appended.

In the drawings, Figure 1 is a side elevation of a separator embodying the present invention. Fig. 2 is a longitudinal sectional view of the same. Fig. 3 is a vertical cross-section taken on the line 3 3 of Fig. 2. Fig. 4 is a vertical section through the amalgam arrester or trap.

Similar numerals of reference designate corresponding parts in all the figures of the drawings.

In carrying out the invention a supporting-frame is provided which consists of standards 10, connected by stringers or braces 11.

Upon this frame is rotatably supported an amalgamator 12, which is in the form of an open-ended cylindrical casing. The ends of

this casing are provided with spiders 13, carrying centrally-disposed sleeves 14, that receive the ends of journals 15, said journals being arranged in suitable boxes 16, located upon the supporting-frame, so that the casing will preferably be disposed at an inclina- 50 55

The casing 12 is constructed of a plurality of detachable sections 12^a, and as each of these sections is of substantially the same construction but one will be described. The 60 walls of the section are preferably made of sheet metal and have their interior surfaces coated with suitable substances having an affinity for gold—as, for instance, quicksilver. Seamed to one end of the section is an 65 inwardly-extending annular rim 17, to which is bolted or otherwise detachably secured an annular stop-flange 18, which carries an offset inwardly-projecting retarding-collar 19, that is spaced from the inner face of the section-wall, and thus forms an annular pocket 70 75 80 85 90 95 20. This retarding-collar is provided with escape-orifices 21, which are arranged at an inclination to the edges of the same, and inclined conveyer-wings 22 are located at the opposite side edges of said escape openings or orifices and project from both faces of the retarding-collars, so that a plurality will thus extend into the pocket 20, while another set will project from the inner face of the collar. Located longitudinally upon the inner face of the section-wall are stirrer-ribs 23, that extend the entire length of the section, and thus have portions located in the pocket 20. These stirrer-ribs are arranged between the escape-openings 21 of the retarding-collar, as clearly indicated in Figs. 2 and 3. The casing is formed of a plurality of sections, the ends of which are arranged in overlapping relation and are detachably secured together by bolts 24 or other suitable fastening means to provide a rigid and liquid-tight joint. The outer or inlet end of the first section is preferably provided with an inwardly-extending retaining-rim 25, and the opposite or discharge end is preferably provided with a cuff 26, to which the spider 13 is secured. The journal at the discharge end of the device is prolonged, so

that it will extend beyond the casing, and may be provided with any suitable driving means, such as a pulley 27, keyed or otherwise secured to the journal, or a handle, as indicated 5 at 28.

The material is introduced into the casing by means of an inclined slush-slue 29, that is secured to the supporting-frame and has its inner end projecting into the receiving 10 end of the casing, the spider at said end being inset, so as not to interfere with the sluice. A hopper 30 is arranged above this sluice, and a water-supply pipe 31 has its discharge end communicating with said sluice in front 15 of the hopper.

For the purpose of preventing the escape of any amalgam or quicksilver which may become detached during the operation of the machine an arresting receptacle or trap 32 is 20 provided below the discharge end of the casing, a funnel 33, secured to the supporting-frame, conducting the discharging material to the same. This receptacle or trap, as 25 clearly illustrated in Fig. 4, consists of a conical bottom 34 and an annular upstanding side wall 35. The bottom is provided with a series of annular grooves or pockets 36, the lower side walls 37 of which are of substantially the same height as the upper side walls. 30 This receptacle is located above or upon the upper end of a tailings-discharge trough 38.

In operation the casing is rotated by any suitable means, as above described, and the material is introduced into the hopper 30. 35 Water from any suitable source is then admitted to the sluice 29 through the supply-pipe 31 and mixing with the material at the bottom of the hopper forms a slush, which gravitates into the first section of the casing. 40 As this casing is rotated the material comes into contact with the quicksilver upon the interior face and the gold contained therein will amalgamate with said quicksilver in a manner well understood. The stirrer-ribs 23 45 keep the material in a state of agitation, and thus bring all the portions thereof into contact with the quicksilver. The slush is held back by the stop-flange 18 and the retarding-collar 19, which prevents the too-rapid discharge of 50 the material. The conveyer-wings 22, however, prevent the solid material from packing into the pockets and throw the same into the escape-openings, from which it is carried into the next section, and so on through the 55 casing. This violent agitation, however, tends to remove some of the quicksilver and amalgam, which discharging with the tailings passes through the funnel 33 and into the trap 32. Being heavier than the refuse, 60 it gravitates to the bottom and is caught in the receiving pockets or grooves, while the residue flows over the edge of the receptacle and discharges into the trough 38. When it is desired to cleanse the receptacle, the sections are taken apart and the interior walls 65 are thoroughly scraped. They are then re-

coated with the quicksilver and fastened together. The gold is recovered by any well-known process.

By this construction a very simple machine 70 is provided, which by careful test has been found to thoroughly remove the fine particles of gold contained in auriferous earth. It has been found that it will operate in substantially a horizontal position, and while the device is shown as constructed of two sections 75 it will be readily understood that more or less may be employed, as desired.

From the foregoing it is thought that the construction, operation, and many advantages of the herein-described invention will be apparent to those skilled in the art without further description, and it will be understood that various changes in the size, shape, proportion, and minor details of construction 80 85 may be resorted to without departing from the spirit or sacrificing any of the advantages of the invention.

Having thus described my invention, what I claim as new, and desire to secure by Letters 90 Patent, is—

1. In an ore-separator, the combination with a casing, of a stop-flange located in the casing, and a retarding-collar carried by the flange and spaced from the inner face of the 95 casing to form a holding-pocket, said collar being provided with an escape-opening.

2. In an ore-separator, the combination with a casing, of a stop-flange located in the casing, and a retarding-collar carried by the 100 flange and spaced from the inner face of the casing to form a holding-pocket, said collar being provided with an inclined escape-opening.

3. In an ore-separator, the combination with 105 a casing, of an annular stop-flange located in the casing, a retarding-collar carried by the flange and spaced from the inner face of the casing to form a holding-pocket, and wings carried by said retarding-collar and projecting 110 into the pocket.

4. In an ore-separator, the combination with a casing, of an annular stop-flange located in the casing, a retarding-collar carried by the flange and spaced from the inner face of the 115 casing to form a holding-pocket, said collar being provided with an escape-opening, and a wing carried by said retarding-collar, said wing being located contiguous to the escape-opening and projecting into the pocket.

5. In an ore-separator, the combination with a rotatable casing, of an annular stop-flange located in the casing, a retarding-collar carried by the flange and spaced from the inner face of the casing to form an annular pocket, 125 and inclined wings carried by the retarding-collar and projecting from both faces thereof.

6. In an ore-separator, the combination with a rotatable casing, of an annular stop-flange located in the casing, a retarding-collar carried by the flange and spaced from the inner 130 face of the casing to form an annular pocket,

said collar being provided with a plurality of inclined escape-openings, and inclined wings carried by the retarding-collar and arranged adjacent to the escape-openings, said wings 5 projecting from both faces of the collar.

7. In an ore-separator, the combination with an open-ended rotatable casing carrying journals at its end, of an intermediate annular stop-flange arranged upon the interior of the 10 casing, an annular retarding-collar carried by the stop-flange and spaced from the casing, said collar being provided with inclined escape-openings, inclined wings carried by the collar and projecting from both faces 15 thereof, and stirrer-ribs located longitudinally upon the inner face of the casing and projecting into the space between the collar and the casing-wall.

8. In an ore-separator, the combination with 20 an open-ended rotatable casing carrying journals at its ends, of an intermediate annular stop-flange arranged upon the interior of the casing, an annular retarding-collar detachably secured to the stop-flange and spaced

from the casing, said collar being provided 25 with inclined escape-openings, inclined wings carried by the collar and projecting from both faces thereof, and stirrer-ribs located longitudinally upon the inner face of the casing, and projecting into the space between 30 the collar and the casing-wall.

9. In an ore-separator, the combination with a casing, of a stop-flange located in the casing, a retarding-collar carried by the flange and spaced from the inner face of the casing 35 to form a pocket, said collar having a plurality of openings therethrough, a plurality of wings carried by the flange and disposed within the pocket, and a rib located longitudinally upon the inner face of the casing and 40 having one end arranged within the pocket.

In testimony that I claim the foregoing as my own I have hereto affixed my signature in the presence of two witnesses.

FREDERICK R. WATERS.
